FURNACE JACK

Arnett Byers, East Chicago, Ind.

Application September 16, 1943, Serial No. 502,653

4 Claims. (Cl. 214—100)

My invention relates to improvements in furnace jacks and it more especially includes the features pointed out in the annexed claims.

The purpose of my invention is to provide self-contained means that will facilitate the assembling of residence furnaces; that instead of using three or four men to assemble the top sections of a furnace I am able to do the same job in a much shorter time by a single man in cooperation with my lifting means. The device is equally operable under any other circumstances where heavy castings need to be lifted to a higher plane. These top sections of furnaces weigh several hundred pounds and besides being very heavy they are exceedingly awkward to handle.

With these and other related ends in view I illustrate on the accompanying drawings such instances of adaptation as will show the broad features of the invention without limiting myself to the specific details shown thereon and described herein.

Fig. 1 is a side elevation of my device in position alongside of a residence furnace.

Fig. 2 is a front elevation of the device shown in Fig. 1, in direct projection.

Fig. 3 is a side elevation of the upper end of the device.

Fig. 4 is a detached elevation of the hook upper end of the inclined plane.

Fig. 5 is a plan view of the lower end of the device.

Fig. 6 is a side elevation of the lower end of the incline.

Fig. 7 is a side elevation of the lifting jack.

Fig. 8 is an end elevation in section of the lower portion of the incline.

Fig. 9 is an end elevation partly in section of the extreme upper end of the device.

In the commercialization of my device I may use whatever changes in structure and operation of parts that the exigencies of varying conditions may demand without departing from the broad spirit of the invention.

A residence furnace 1, shown in Figure 1, has the separate sections 2 and the usual smoke outlet 3. In order to put the top sections into position easily I have provided an inclined plane made up of two strong planks 7. These planks are held together at the bottom end by a cross bar 18 and at the top end by the angle bar 8. At the extreme upper end there are two extensions 6, these terminate in hook ends 5. The hooks 5 serve to hold the planks in position with the hooks engaging the ledges 4 of the sections 2. The angle bar 8 at the top has openings for

the hook ends 22 of the jack rods 9. There are two of these rods, one on each side of the plank center.

A slightly curved sliding member 10 straddles the planks 7 and it is held against sidewise movement by the pins 12 which engage the side edges of the planks. The curved portion 10 has side extensions 16 which are provided with openings 21 for the reception of the hook ends 17 of the jack swivel 19. There is one of these swivels for each one of the jack rods 9. The hook extension 17 enter the openings 21. The part 10 has a bracket 11 with a brace 15 welded onto it. The lower leg of the bracket 11 rests on the boards 7 and it serves to hold the part 10 in position on the planks to form a support for the sections 2 as they are rolled into position, one by one and then raised.

There is a jack 13 for each rod 9 and each jack 20 has one of the ferrules or swivels 19 which engage the extensions 16. They are free to turn on a projection of the sheet metal casing of the jacks 13. As shown the jacks 13 are each provided with an operating handle 14. The jack rods 9 pass entirely through the jacks. The structure of these jacks is conventional. They are provided with a pair of loose floating dogs 20 that alternately cooperate with a spring 24 and a washer 23 through which the jack rods 9 pass. The movement of the lever 14 with each downward push engages the washer and it in turn grips the rod 9 moving the section a short distance up. On the reverse movement of the handle the loose dogs prevent the load slipping back on the planks. The next movement of the lever will again advance the support 10 upward, carrying with it one of the sections 2. After a section 2 has been placed on top of the next section, as shown by dotted lines in Fig. 1, and the bottom end of the boards is shifted accordingly along the floor. When a section has been lifted into place a slight release of the dogs 20 will let the jacks and the connected support 10 slide to the bottom ready to receive the next section.

Should it be desired the two handles 14 may be interconnected by any conventional coupling bar (not shown) so that a single movement will operate both jacks at the same time.

My device is quite simple and inexpensive in contrast to the use of threaded or notched rods. The wooden planks 7 may be substituted by metal plates if desired.

What I claim is:

1. A portable inclined plane comprising a main

member adapted to reach from an elevation to the ground, means at the elevated end to engage a projection of the object being served, a movable member at the other end of the incline, means comprising parallel rods connecting the movable member with the upper end of the incline, and means for sliding the movable member and a load up the incline by intermittent frictional impulses on the connecting means.

2. A furnace jack which comprises a weight carrying incline, means for moving a weighted object up the incline said means including a frictional applied jack, a duplicate jack, a separate traveling rod for each jack, means for joining the rods at the bottom end of the incline said means being adapted to hold the object to be moved up the incline, means for holding the upper end of the incline against movement on the object that is being served and means for intermittently operating the jacks.

20

3. A portable incline which comprises, means at one end for resting it elevated on a portion of a furnace, a pair of parallel rods, a movable member at the other end of the incline operative on said rods adapted to engage an object to be placed on the furnace, and means acting on said rods for intermittently moving the furnace part up the incline.

4. An incline for lifting heavy articles onto a higher plane which comprises a central member, a cross member at the top, a smooth rod removably secured to the cross member on each side of the center member, a sliding member adapted to be moved lengthwise of the central member, means for attaching said last member to said rods, and a cooperating jack on each rod for moving the slidable member toward the other end of the central member.
